UNITED STATES PATENT OFFICE

WALTER E. ADAMS, OF LOS ANGELES, CALIFORNIA

CIRCULATION SYSTEM FOR ENGINES

Application filed March 27, 1928. Serial No. 265,060.

This invention relates to an improved circulation system and means for engines, and particularly internal combustion engines.

The invention has for an object the provision of a cooling system and means which is effective to the end that those parts of a motor which work under the greatest heat are properly cooled. Internal combustion engines are sometimes subject to what is known as cracking of the cylinder block due to overheating of the engine. My system has for an object a cooling method as well as a means which will in a large measure overcome this trouble to the end that cracked cylinder blocks rarely occur. My system and means may be utilized as an attachment for existing engines or it may be formed integral with the engine block at the time the engine block is cast.

I have found that in the average truck, the truck drivers often work their engines to the extreme limits in the hauling of heavy loads. It often happens that truck engines will run in low gear for hours at a time and unless the driver is careful, the cooling medium, if it happens to be water, will become extremely hot and no longer effect a proper cooling of the engine with the result that a crack will occur in the block and the engine is rendered practically useless thereafter. The cooling medium, which is usually water, has an entrance within the engine block usually on the exhaust side. This water is generally forced into the engine block from a radiator through the medium of a pump. This pump is adapted to force the water into the engine block under pressure and the inventor has found that this water pressure is usually sufficient to force the water to the opposite side of the engine, that is, to the intake valve side which is generally cool, with the result that the hottest side of the engine is in a measure neglected or at best the water is warm or hot by the time it reaches the exhaust side of the engine, or the water may "back up" on the exhaust side of the engine and prevent the cooler water from actual contact with the cylinder walls in the exhaust valve housings. Quite naturally the exhaust valve side would then overheat and a crack would probably result if the engine had a long continued use under

these operating conditions. Another factor would be that steam would form above the surface of the water and tend to prevent actual circulation around the hottest portion of the engine.

My invention has for another object the provision of means which will direct the water to where it is most needed to the end that the hottest side of the engine will have a proper circulation of cool water.

Other objects will appear as the specification proceeds and with such objects in view, the invention consists in the novel and useful provision, formation, construction, association and relative arrangement of parts, members and features, all as shown in a certain embodiment in the accompanying drawing, described generally, and more particularly pointed out in the claims.

In the drawing:

Figure 1 is a top plan view of an engine block with the head removed and showing the invention incorporated within the block,

Figure 2 is a transverse sectional view of the engine on the line 2—2 of Figure 1, and

Figure 3 is a perspective view of a means which may be used in practicing the invention.

Referring now with particularity to the drawing, the improved circulation system and means is designated as an entirety by A, and the same may include a radiator *a* which receives water or other liquid from the cylinder head *b* of an engine *c* and which water is run through the radiator for the purpose of cooling the same and delivered at the lower extremity of the radiator to a circulation pump *d* which pump in turn delivers the water within the engine *c* through means *e*. This means *e* is shown in Figure 3, and the same includes a curved tube 1 flanged at one end 2, and the opposite end is capped or closed, as shown at 3. Said tube is provided with one or more openings 4 adjacent the capped or closed end 3. In the present instance three openings are provided and arranged substantially 90° apart. Ordinarily the pipe 5 leading from the pump *d* communicates directly with the interior of the engine block. It will be seen from the figures that the device *e* is inserted

within the engine block so that the perforated end thereof lies adjacent the intake valve housings shown at 6. The pipe 5 is then connected to the flange 2 in the usual manner, that is, by passing bolts through bolt openings 7 in the flange 2 and in the flange on the end of the pipe 5 and then securing the same by nuts. The motor illustrated in Figure 1 is of the dual valve type having two intake 10 valves for each cylinder as well as two exhaust valves for each cylinder. Ordinarily water from the radiator *a* is forced at high velocity by the pump within the engine block and the same moves directly across the engine 15 block, as indicated by the arrow 8 to the opposite side of the engine block and flows between the intake valve housings and the cylinders and thence around in contact with the exhaust valve housings and the cylinders. 20 This, of course, causes the coolest water to contact with the coolest part of the motor. With my system and by utilizing the means *e*, the water would be divided and one-third of said stream of water would flow in the direction 25 of the arrow 8 and the other two-thirds would flow in the direction of the arrows 9 and 10; thus cool water would be caused to contact as between the exhaust valve housings and the cylinder walls. The result will 30 be that the cool water will circulate generally, as indicated by the arrows 11. It will be noted that the openings 4 are close to the tops of the valve housings or that portion which normally receives the valve head. This is the portion 35 of greatest heat and the cool water is brought directly in contact with this portion.

It is obvious that the means *e* might be cast in the engine block or that the point of entrance of the water within the engine block 40 might be raised and suitable means for directing the path of flow of the water in departure from use of the precise features of the device *e*, and that these changes are contemplated without departing from the true 45 spirit of the invention.

Having thus disclosed my invention what I claim and desire to secure by Letters Patent is:

1. The combination with a water cooled engine, of a tube received in the water jacket of said engine, said tube being capped at one end and formed with an orifice opening, and means for directing water under pressure through said tube for outward flow through 55 said orifice opening.

2. The combination with the water jacket of an internal combustion engine, of a tube received within said water jacket, said tube being provided with orifice openings, and 60 means for directing water under pressure into said tube, said orifice openings splitting the path of flow of said water into a plurality of directions.

3. The combination with an internal combustion engine having the usual intake valves

and exhaust valves and water jacket, of a curved tube, within said water jacket, and provided with a plurality of orifice openings; said orifice openings being adjacent the intake valve housings, and means for forcing 70 water under pressure through said tube and out said orifice openings, said orifice openings dividing the stream of water to direct the path of flow of said water within said jacket.

4. The combination with an internal combustion engine having the usual water jacket surrounding the usual exhaust and intake valve housings and cylinder walls, of a tube within said water jacket provided with a closed end and formed with a plurality of orifice openings, and means for forcing water under pressure through said tube and out said orifice openings, said tube being positioned adjacent the tops of the valve housings to thereby direct the cool water against the hot- 80 test part of the engine.

In testimony whereof, I have signed my name to this specification at Los Angeles, California, this 15th day of March, 1928.

WALTER E. ADAMS.
